UNITED STATES PATENT OFFICE.

JOHN E. CHAMBERS, OF SHELBYVILLE, INDIANA.

COMBINED GAS-STOVE AND FIRELESS COOKER.

1,225,769.

Specification of Letters Patent. Patented May 15, 1917.

Application filed March 30, 1911. Serial No. 618,047.

To all whom it may concern:

Be it known that I, JOHN E. CHAMBERS, a citizen of the United States, residing at Shelbyville, in the county of Shelby and 5 State of Indiana, have invented certain new and useful Improvements in Combined Gas-Stoves and Fireless Cookers, of which the following is a specification, reference being had therein to the accompanying drawing.

10 This invention relates to improvements in a combined gas stove and fireless cooker.

One of the objects of the present invention is the provision of a device of this character which can be used when desired as an 15 ordinary gas stove and for all the purposes and in the same manner as such stoves are ordinarily used, and which can also when desired be used as a fireless cooker, the burners of the stove being utilized to produce the 20 initial heat.

A further object of the present invention is the provision in a device of this character of improved means for preventing the 25 passage of fuel to the burner in the cooking compartment when such compartment is adapted for use as a fireless cooker.

A further object of the invention is the provision in a device of this character of a cooking compartment having a burner 30 therein and provided with an opening which is normally open when the device is to be used as an ordinary gas stove, in combination with a door or damper for closing said opening when the device is to be used as a 35 fireless cooker, and operating means for such door or damper of such a construction as to shut off the flow of fuel to the burner as the door or damper is closed, such operating means being, however, so connected to the 40 fuel valve as to permit any desired adjustment thereof as long as the door or damper is in open position.

A further object of the present invention is the provision of a device of this character 45 which is made up of a plurality of similarly formed units so that the stove can be formed with any desired number of cooking compartments.

Other objects of the invention will be apparent from the detailed description hereinafter when read in connection with the 50 accompanying drawings forming a part hereof, wherein a convenient embodiment of the invention is illustrated and wherein like numerals of reference refer to similar parts in the several views.

In the drawings,

Figure 1 is a front elevation of a gas stove constructed in accordance with the present invention,

60

Fig. 2 is a longitudinal section thereof,

Fig. 3 is a fragmentary sectional view showing the construction of the lower portion of one of the cooking compartments;

Fig. 3^a is a fragmentary sectional view 65 showing the construction of the upper portion of one of the cooking compartments, and a band for coupling the compartments;

Fig. 4 is a fragmentary sectional view of the upper and lower compartments in 70 coupled position;

Figs. 5, 6, and 7 are detail views of the fuel valve and the operating mechanism therefor.

Fig. 8 is a section on line 8—8 of Fig. 2, 75 parts being shown in elevation.

Fig. 9 is a detail view of one of the parts removed.

Referring now more particularly to the drawings, A designates a combined gas stove 80 and fireless cooker constructed in accordance with the present invention, said stove comprising in the form illustrated, two superposed compartments B and C, which may be used in any manner in which the ordinary 85 cooking compartments of a gas stove can be used and which may also be used as a fireless cooker when desired. For the purposes of illustration, I have shown the stove as consisting of two cooking compartments 90 only, but from the detailed description hereinafter, it will be understood that the stove may be made up of as many compartments as desired and that such compartments may be constructed according to the uses for 95 which they are designed.

The compartments B and C are similar in construction, each comprising a body D, the front, top, bottom and side walls of which are formed of separated sheets of metal between which is interposed a suitable packing of heat insulating material. The front of the body D of each of the compartments B and C is provided with the usual door opening therein which is adapted to be closed by 100 a door D', preferably formed of sheet metal such door being of a hollow formation and having a filling of heat insulating material. The extreme upper portions of the side walls of each of the cooking compartments are 105 provided with inwardly off-set portions d forming a rabbet extending along the upper

edges of the sides of the compartment. The top sheet of each compartment is provided with downwardly extending flanges which project downwardly inside of the offset portions d , above referred to and the upper edge 5 of the front wall of the compartment, and are riveted thereto with the upper surface of said top sheet flush with the upper edges of said off-set portions and the front wall 10 of the compartment. Seated in the rabbet thus formed along the sides of each of the cooking compartments is a U-shaped band or frame E, such band being of such thickness that the side portions thereof 15 substantially fill the rabbets so that the exterior of said side portions thereof will lie flush with the exterior of the side surfaces of the compartment. The band E is of a width to project above the upper edges of the off-set 20 portions d of the sides of the cooking compartment and the upper edge of the front wall of the compartment. The band E is secured in the rabbet by suitable bolts, or similar fastening devices which pass there- 25 through and engage the off-set portions d heretofore referred to. Projecting downwardly from the body of each of the compartments along the side edges thereof is a flange d' which is formed by off-setting the 30 lower portions of the sides of the compartment inwardly to the same extent as the upper portions of the sides are off-set to form the off-set portions d . The bottom sheet of each compartment is provided with downwardly extending flanges at the sides thereof 35 which are adapted to fit within the flanges d' , of the body, and to be rigidly secured thereto by fastening devices of any suitable character.

40 Secured to the rear wall of the body D of each of the cooking compartments and extending longitudinally thereof is an open ended flue F, the ends of which project slightly beyond the top and bottom of the body and the upper end of which is preferably made slightly smaller than the lower end thereof. The upper portion of the body D of each of the compartments is provided in the rear wall thereof with a vent opening 45 G which communicates with a small vent tube G' which projects into the flue F and is preferably provided with a downwardly beveled outer end. The vent pipe G' is smaller than the interior of the flue so as 50 not to impede the passage of air and gases therethrough. Positioned within the interior of the body D of each compartment and over the inlet end of the vent opening G is a sheet metal guard or shield, a portion 55 of which overlies the top of the cooking compartment and is spaced therefrom. The portion of the shield which overlies the inlet end of the vent tube is preferably imperforate while perforations are formed in the 60 portion which overlies the top of the cook- 65

ing compartment, thus preventing the heated gases in the cooking compartment from passing directly out through the vent opening therein. The body D of each of the cooking compartments is provided centrally of the bottom thereof with a small draft opening H therein and positioned within the interior of the compartment over said draft opening is a gas burner I of any suitable construction, the feed pipe I' of 70 which passes through the front wall of the compartment. Positioned within the interior of each compartment over the burner therein is a deflector plate I² which serves to cause an even distribution of heat within 75 the compartment.

K designates the base of the stove which comprises a band of a size to receive the flanges d' depending from the bottom of the lowermost compartment and from which depends the usual supporting legs K'. In assembling the stove the lowermost compartment is fitted onto the base with the flanges d' depending from the lower edges thereof 80 extending into the band of the base and with the shoulders formed at the juncture of the sides of the compartment and the flanges d' extending downwardly therefrom resting directly upon the upper edge of the band 85 of the base. With the parts in this position 90 the lowermost compartment is rigidly secured to the base by means of suitable securing bolts which pass through the sides of the band of the base and the side flanges depending from the bottom of the compartment. 95 The upper compartment is then fitted onto the lower compartment with the flanges d' extending from the lower portion of said upper compartment fitting within the U-shaped band E which is secured to the top 100 of the lower compartment and with the shoulders formed adjacent the tops of the flanges d' of the upper compartment resting directly upon the upper edge of said band. 105 As the flanges d' depend only from the sides and front of the lower portion of the upper cooking compartment, and as the band or frame E extends only around the front and sides of the adjacent portions of the upper and lower cooking compartments, it will be 110 seen that there will be provided at the back of the cooker an open space between the bottom of the upper cooking compartment and the top of the lower cooking compartment through which air can pass to the draft 115 opening H in the bottom of the upper cooking compartment. With the parts in this position securing bolts are passed through the side portions of the band E and the flanges of the upper compartment which are 120 positioned within said band. When the compartments B and C are assembled in this manner, the lower portion of the flue F of the upper compartment will telescopically 125 engage the upper portion of the flue F of 130

the lower compartment, thus forming a continuous flue common to both cooking compartments. It will of course be understood that while I have shown and described the 5 stove as comprising but two compartments, the stove may be built up to any desired size by using any number of such compartments. If desired the upper portion of the flue of the topmost compartment may be 10 connected to any suitable flue or chimney to carry off the obnoxious fumes. The top of the uppermost cooking compartment is finished by securing within the U-shaped band E which is secured around the upper edge 15 thereof a sheet metal plate L, such plate being provided with depending flanges which snugly fit within the frame E at the top of the compartment and are rigidly secured thereto in any desired manner with 20 the top of the plate L, substantially flush with the upper edges of said frame. Pivotally secured to the outer end of the vent pipe G' of each of the cooking compartments is a damper M which is adapted in one position 25 to lie flat upon the beveled outer end of said vent pipe so as to close the end thereof, said damper being preferably of metal and having an inner facing of heat insulating material m'. The dampers M are each provided 30 with an arm projecting laterally therefrom which is pivotally connected to one end of a link m, the other end of which is pivotally connected to one arm of a bell crank lever N which is pivoted to a suitable 35 projection extending from the rear wall of the cooking compartment. Pivotally connected to the free ends of the bell crank levers N and extending forward to a point in advance of the front of the cooking 40 compartments are rods N', the rod N' for operating the damper M of the upper cooking compartment B being located in the space between the top and bottom of the cooking compartments B and C and extending 45 through the front portion of the band E heretofore described, and the rod for operating the damper of the lower compartment C passing under the bottom of said compartment and through an opening in the 50 ring or band of the base K of the stove.

O designates a gas supply pipe which is provided with laterally extending branches O' which are positioned in front of the cooking compartments B and C adjacent 55 the lower portions thereof. Connected to each of the laterally extending branch pipes O' is a valve casing P from which a gas discharge pipe p extends into an air and gas mixer P' which may be of any well 60 known type and which is provided with a tubular extension which is adapted to slip over the projecting end of one of the burner supply pipes I' and to be detachably secured thereto in any suitable manner. Positioned 65 within each of the valve casings P and con-

trolling the flow of gas therethrough from the branch supply pipe O' is a valve Q which is provided with an elongated stem rotatable therewith to the upper end of which is rigidly secured a laterally projecting operating handle Q' the operating handle being arranged to lie parallel with the branch supply pipe O' when the valve is in a position to prevent the flow of gas to the burner. Loosely mounted upon the 70 elongated shank of each of the gas valves Q is a lever R which is provided with an arm R' which extends downwardly therefrom and is positioned substantially at right angles thereto, the lower end of said 75 arm being curved so as to partially underlie and contact with the branch pipe O' when the lever occupies a position at right angles to said supply pipe. The lower ends of the arms R' which extend from the levers just described, are pivotally connected to the front ends of the damper operating rods N' heretofore described, so that by 80 actuating the levers R the dampers M may be operated to open the closed ends of the 85 vent pipes of the cooking compartments. Each of the levers R is provided with an outwardly projecting lug r which is adapted to lie alongside of the operating handle Q' of the valve Q upon the shank of which 90 said lever is pivotally mounted.

The levers R normally occupy positions at substantially right angles to the branch supply pipes O', and when in this position the dampers M controlled thereby are in 95 their open positions so as to permit the free passage of gases from the cooking compartments. The levers are always maintained in this position when the cooking compartments are to be used in the manner of cooking 100 compartments of the ordinary gas stove, and it will be seen that while the levers occupy this position, the handles of the gas valves may be shifted to cut off the flow of gas to the burners to any desired 105 extent, without in any way affecting the position of the dampers controlling the vent passages. This is important as in the use of a gas stove it is frequently desired 110 to use a very low flame and to at the same time have the vent passage open. When either of the cooking compartments is to be used as a fireless cooker, the lever R of such compartment is shifted to a position 115 substantially parallel to the front of the compartment. During this movement of the lever R, the lug r will engage the handle Q' of the valve Q and move such valve to its closed position, thereby cutting off the flow of gas to the burner. It will thus 120 be seen that it will be impossible to close the damper to convert the device into a fireless cooker without at the same time automatically cutting off the flow of fuel to the burner, and at the same time when either 125 130

of the compartments is to be used as a gas stove, it will be seen that the gas supply valve may be adjusted to any desired position without in any way restricting the vent 5 passage leading from the compartment.

From the above described construction it will be apparent that the device may be made up of as many compartments as desired and that any one or all of such compartments 10 may be at any time utilized as a gas stove or as a fireless cooker.

While a convenient embodiment of the invention is illustrated in the accompanying drawings, it will be understood that 15 many changes may be made to the form and construction herein shown without in any way departing from the spirit and scope of the invention as defined in the appended claims.

20 I claim—

1. In a combined stove and fireless cooker, a cooking compartment provided with an opening therein leading to the exterior thereof, a burner in said cooking compartment, a 25 fuel valve controlling the passage of fuel to said burner, said valve being provided with a rotatable stem, a damper for the opening in the cooking compartment, operating mechanism for the damper including an operating 30 handle loosely mounted on the stem of the fuel valve, said operating handle and valve stem being provided with coöperating portions acting to turn the valve to closed position when the operating handle is shifted 35 to move the damper to closed position and permitting free action of the valve independent of the damper operating mechanism.

2. In a combined stove and fireless cooker, a cooking compartment provided with an 40 opening therein leading to the exterior thereof, a burner in said cooking compartment, a fuel valve controlling the passage of fuel to said burner, said valve being provided with a rotatable stem, and an operating handle 45 projecting laterally therefrom, a damper for the opening in the cooking compartment, operating mechanism for the damper including a lever loosely mounted on the stem of the fuel valve and provided with a projection 50 normally positioned alongside of the operating handle of the fuel valve so as to contact therewith as the lever is shifted.

3. In a combined stove and fireless cooker, a cooking compartment, provided with an 55 opening leading to the outside, a burner for

said cooking compartment, a fuel valve controlling the passage of fuel to said burner, a handle for said valve, a closure for the opening in the cooking compartment, operating mechanism for the closure including an operating handle, the said handles being mounted to rotate about a common vertical axis, and operatively associated means whereby a movement of one handle in one direction will result in a movement of the other 60 handle in the same direction, and said connection permitting independent movement of one of said handles.

4. In a combined stove and fireless cooker, the combination of a cooking compartment 70 provided with an opening leading to the outside, a damper for controlling said opening, a burner for the cooking compartment, a valve for controlling the fuel supply to said burner, an operating handle for the valve, 75 operating mechanism for the damper, an operating handle for said mechanism, said operating handles being mounted to rotate about a common axis, and an operative engagement between said handles whereby as 80 the damper is moved to closed position, the burner valve is simultaneously moved to closed position, and said operative engagement permitting free independent movement of the fuel supply valve when the damper is 85 open.

5. In a combined stove and fireless cooker, the combination of a cooking compartment provided with a vent opening, a damper for 90 said opening, a burner for the compartment, fuel supply means for the burner, a rotatable valve for regulating the fuel supply, a handle for said valve, operating mechanism for the damper including a handle, said handles being arranged adjacent to one another and 95 a connected part of one handle constituting a support for the other handle, the handle for the fuel valve being adapted to move independently of the handle for operating the damper, and inter-engaging means carried 100 by the handles whereby as the damper handle is moved to close the damper the fuel supply valve is moved to closed position.

In testimony whereof I affix my signature in presence of two witnesses.

JOHN E. CHAMBERS.
